UNITED STATES PATENT OFFICE.

EARL A. BESSOM AND RAYMOND M. ANDERSON, OF CHICAGO, ILLINOIS, ASSIGNEES TO STROMBERG MOTOR DEVICES COMPANY, OF CHICAGO, ILLINOIS, A CORPORATION OF ILLINOIS.

CARBURETER.

1,134,942.

Specification of Letters Patent.

Patented Apr. 6, 1915.

Application filed February 14, 1912. Serial No. 677,514.

To all whom it may concern:

Be it known that we, EARL A. BESSOM and RAYMOND M. ANDERSON, citizens of the United States, residing at Chicago, in the county of Cook and State of Illinois, have invented certain new and useful Improvements in Carbureters, of which the following is a full, clear, concise, and exact description, reference being had to the accompanying drawings, forming a part of this specification.

Our invention relates to charge forming devices for internal combustion engines and is concerned with the control of the fuel supply, relative to the air supply, under the different running conditions of the engine, such as high speed, low speed, and starting.

Our invention has to do particularly with the provision of means for accommodating the charge to sudden variations in engine conditions.

We are aware that in the prior art there are found devices which automatically lend themselves to engine conditions, but the great difficulty has been that in these prior devices considerable time was consumed before the response.

It is well known that in order to supply an engine with an efficient charge, there must be certain definite proportions between constituents of the charge, fuel and air, and it is the primary object of our invention to maintain the proper proportions at all times regardless of the spasmodic variations which are likely to occur in the engine.

As in substantially all present day carbureters, the carbureter of our invention comprises an air passageway with which a fuel nozzle is associated, the flow from the fuel nozzle being due to the difference in pressure at that point and the pressure upon the top of the liquid fuel commonly employed in a reservoir connected with the nozzle. The pressure in the air passage depends upon the suction created by the engine and it is this suction which secures the pneumatic potential for exciting the fuel flow. The supply to the engine is controlled by a throttle. Upon starting, the throttle valve is opened and it will be understood that at this time it is desirable that a rich mixture be secured. In other words, a full supply for the nozzle upon starting secures great efficiency and as will be described presently, we employ the pressure conditions deter-

mined by the position of the valve itself for the purpose of securing this full and ready supply. It has been found in devices of the prior art that if a fuel nozzle and the associated parts were so constructed as to give a fully and ready supply upon starting, the efficiency at high speeds would be greatly impaired and a very considerable waste of fuel would be entailed. However, with the control such as we propose the supply at higher speeds is properly retarded and the most advantageous proportions are secured under the various conditions.

The surface of the liquid fuel in the reservoir is exposed to the atmosphere. In order to carry out our inventions, however, we control the connections between the reservoir and the atmosphere and we provide connection between the top of the reservoir, that is between that part of the reservoir over the surface of the liquid fuel, and the air passage. The connection between the top of the reservoir and the air passage, is under most conditions, considered to be above or on the engine side of the throttle. Under special conditions, as will be explained, connection is also made with the other side of the throttle. It will appear that when the throttle is nearly closed the vacuum on the engine side thereof is greater than when it is wide open and, theoretically, the vacuum would be at its maximum if the engine were turned over on closed throttle. Viewing the arrangement then from its theoretical standpoint it will be understood that as the vacuum on the engine side of the throttle is increased, so is the pressure on the top of the liquid fuel in the reservoir decreased. It will appear, however, that this increase and decrease does not occur in direct proportion, and for this reason rich mixtures may be secured at starting and leaner mixtures may be secured at higher speeds although the amount of the total charge is larger in the latter instance. The sum and substance of the result we secure is that regardless of the speed of the engine the definite and proper mixture is maintained, while at the same time, at starting, sufficiently more fuel is provided in proportion to the air in order that the proper rich mixture may be had. It will be seen that the operation is such that the supply for the nozzle responds accurately and promptly to the variations in any engine conditions, however.

sudden or spasmodic they may be, and in this way the engine may "pick up" sufficiently without any consequent waste of fuel and destruction of the mixture proportions as the higher speeds are obtained.

5 We have illustrated an embodiment of our invention in the accompanying drawings in which—

10 Figure 1 is a vertical axial view through the carbureter; and Fig. 2 is a corresponding detail view showing a modified construction.

15 Like reference characters are applied to the same parts throughout the various figures.

The main structural supporting unit is in the form of a casting 6 which may be considered as being divided into three parts—the main mixing chamber 7, the auxiliary air inlet chamber 8 and the oil inlet chamber 9, the three parts conveniently having their axes in a single plane. The main mixing chamber 7 is supplemented downwardly by an extension 10 which has a central passageway of double conical cross-section, commonly called a "Venturi" tube. The extension 10 is screw-threaded externally for the reception of a sleeve 11 which then extends downwardly and is provided at the bottom with a preferably integral shelf 12. A fuel tube 13 is disposed in axial alignment with the sleeve 11, part of the tube extending upwardly into the sleeve and the other part extending downwardly below the shelf 12. This fuel tube is conveniently cast integral with the sleeve 11 and shelf 12 and is supported therefrom by means of the spider 14. A circular wall 15, preferably of glass, is clamped between the shelf 12 and the body of the casting 6 so as to form an oil float chamber 16, suitable gaskets 17 and 18 being provided to make a tight compartment. The float chamber 16 is connected with the inside of the fuel tube 13 by means of the passageways 19, 19 in the spider 14. Disposed within the float chamber and surrounding the sleeve 11, so as to be in axial alignment with the Venturi tube, is an annular float 20, the position of this float being subject to the amount of oil contained in the chamber. The float chamber 16 is connected with the fuel chamber 9 by means of a passageway 21 and the chamber 9 in turn is connected with a source 55 of oil supply in the following manner: The fuel chamber 9 is provided with a double outlet boss 22, 23, a valve seat member 24 being disposed in the connecting passage between the boss chamber and the fuel chamber. The boss 22 is in axial alignment with the passage leading to the fuel chamber and with a valve to be described. This boss is closed however by the use of a plug 25 and it is provided mostly for structural purposes although, as will be evident to those

skilled in the art, the fuel could be led into this boss if the associated arrangement were so disposed that that would be convenient. The boss 23 is provided with a union 26 from which the pipe 27, leading to the oil supply, extends. A strainer 28 is disposed in the boss 23 so as to prevent impurities from clogging the passage 29, leading to the boss chamber, and subsequent passages.

70 On the top of the casting 6, in axial alignment with the valve opening 30 in the valve seat member 24, a tubular boss 31 is provided and this boss is internally screw-threaded for the reception of a sleeve 32 in which a valve stem 33 is mounted, as clearly 75 illustrated in Fig. 1. At the bottom thereof of this valve stem 33 is provided with a head 34 between which and the sleeve 32 a helical spring 35 is disposed, this spring tending to move the stem downwardly. A 80 valve 36 is carried in this head and the lower end of the valve is tapered for co-operation with the tapered seat for the valve opening 30. The valve, and consequently the stem, is guided at the bottom by means 85 of a suitable spider 37 carried by the valve seat member 24.

Within the fuel chamber 9 a lever 44 is mounted upon a pivot 45, one arm of this lever being bifurcated so as to engage the 90 under side of the head 34 of the stem 33 and the other arm extending through the passageway 21 into the float chamber 16. The end of the lever 44 within the float chamber has pivoted thereto at 46 a link 47 which is attached to the float 20. It will now appear that the oil used for fuel can enter the carbureter by way of the connection 27, passing through the opening 29 and up through the valve opening 30. It 100 then flows over the side of the float chamber and down through the passageway 21. It will be seen that the weight of the float acts in opposition to the spring 35 and as the float rises this opposition will be removed 105 and the spring 35 will tend to close the valve 36 to a greater or less extent. When sufficient oil has entered the float chamber the valve can be closed entirely and when the float subsequently drops it is opened to admit more oil.

110 The fuel tube 13 is provided at the upper end with a nozzle 53 which terminates in the restricted zone of the Venturi tube. At the bottom this fuel tube is provided with 115 the normally closed drain cock 54, and is externally screw-threaded for the reception of the priming cup 55. When the float chamber is flooded, as heretofore described, the oil runs out of the nozzle and drops 120 down to this cup. As the air is drawn through the carbureter, then this excess oil supply is volatilized and a rich mixture is 125 secured for starting purposes.

130 The auxiliary air chamber 8 is provided

with an upward opening in which a spider 56 is disposed, this spider having a number of inlet openings and having its inner edge inwardly beveled as indicated at 57 to form 5 a valve seat. A valve member 58 is secured upon a valve stem 59 which is guided at the top in the central boss 60 on the spider 56 and at the bottom in a sleeve 61 having threaded engagement with the inside of a 10 downwardly extending boss 62 on the main casting. A helical spring 63 surrounds the stem 59 and extends between the under side of the valve member 58 and the top of the sleeve 61. The sleeve has secured thereto a 15 cup 64, as best shown in Fig. 1, which is knurled to form a thumb piece and is provided with a plurality of peripheral slots 65 into any one of which a plunger 66 mounted in a pocket 67 against the tension 20 of a spring 68, may extend so as to hold it in any adjusted position. It will be seen that the manipulation of the cup 64 will result in a change in the tension of the spring 63. For convenience the pocket 67 is formed in a 25 screw 69 which is mounted in the main casting.

It will be seen that part of the side wall of the throat part of the casing in which the throttle is disposed is enlarged as illustrated 30 at 79 and is provided with a screw-threaded port 80 in which a plug 81 engages. This plug is provided with a peripheral groove 82 from which passageways 83 and 84 extend into the air passage of the carburetor. 35 The closed position of the throttle is illustrated in dotted lines and it will be seen that when the throttle is in this position the passageway 83 opens into the air passage above the throttle, that is on the engine side, while 40 the passage 84 opens into the air passage below the throttle. A vertical passageway 85 connects with the annular groove 82 and leads into the float chamber. Except for this outlet and an outlet to the atmosphere 45 the float chamber is air tight. This outlet to the atmosphere is indicated at 86 and is controlled by a manually operated valve 87.

It will now be seen that upon starting, or 50 when it becomes necessary to suddenly increase the speed, the throttle valve is suddenly opened up and there will be an immediate and very considerable decrease in the vacuum on the engine side of the throttle. This allows the atmospheric pressure entering the float 55 chamber through the opening 86 to act with practically its full effectiveness and the maximum amount of fuel is forced out through the nozzle. The necessary rich mixture, with sufficient fuel, is then secured. As the 60 engine is throttled down, however, the vacuum on the engine side of the throttle, thus decreasing the pressure on the top of the liquid in the float chamber and properly retarding the issue from the fuel nozzle. It 65 will be seen that for intermediate positions

of the throttle the effect of the vacuum on the pressure in the float chamber is intermediate. When sudden acceleration is to take place the vacuum above the throttle is almost entirely dissipated for the time 70 being and there will be a sudden rush of fuel from the reservoir to and out of the nozzle.

When it is desired to adjust the positions of the passageways 83 and 84 the plug 81 may be turned so that these passageways 75 may be moved toward and away from the edges of the throttle valve and in fact they may be so adjusted that the throttle valve may positively restrict them.

In Fig. 2 we have illustrated a modified arrangement in which but one passageway is provided, this passageway being shown at 88. The passageway is disposed eccentric in the plug 89 and by turning the plug it is possible to move this passageway up and down so as to adjust its position relative to the throttle valve. In the latter form of our invention it is the idea that the passageway 88 shall be always open to the engine side 90 of the throttle, although it may be restricted by the valve piece itself, and should never be connected with the other side of the throttle. In the position shown in Fig. 2 the throttle valve practically closes the passageway 88 and it will appear that all the operation which has been described applies to this arrangement. The use of the lower passageway in the form of our invention shown in Fig. 1 is somewhat as a shunt or by-pass 95 so that the vacuum above the throttle, with the throttle nearly closed, will not draw back the fuel. In the form of our invention shown in Fig. 2, however, the same result is secured by positively restricting or closing the passageway which is exposed to the pressure on the engine side of the throttle. This provision is made for conditions where the throttle is closed down to create a maximum vacuum on the engine side thereof. 100

The passageways 83, 84 and 85 are properly restricted so that the pneumatic actions which have been described may be secured. We found by experiment that the best action is secured when the passageway 84 is 115 larger than the passageway 83 and when the passageway 85 is larger than the passageway 83 but smaller than the passageway 84. In the specific form of our invention herein shown and described for the purpose of instructing those skilled in the art, we employ a number 48 drill for the passageway 84, a number 51 drill for the passageway 85, and a number 60 drill for the passageway 83. It will be understood, however, that we do 120 not wish to be limited to these particular sizes or their particular relations since efficient operation may be obtained with other specifications. The limitations which are necessarily incurred are found in the ap- 125 130

pended claims wherein our invention is definitely set forth.

We claim—

1. In a carbureter adapted for connection with an engine, an air passage, a throttle in said air passage, a liquid fuel reservoir, a fuel nozzle in said passage and connected with said reservoir, and a connecting passageway confined alone to the zone of the air passage on the engine side of the throttle and the top of said reservoir, said connecting passageway at the passage end terminating in a rotatable plug and having its outlet eccentric therein, said throttle being so disposed in said passage that when closed it may mechanically and positively restrict or close said connecting passageway, and an adjustable atmosphere inlet for said reservoir.
- 10 2. In a carbureter adapted for connection with an engine, an air passage, a throttle in said air passage, a liquid fuel reservoir, a fuel nozzle in said passage and connected with said reservoir, and a connecting passageway confined alone to the zone of the air passage on the engine side of the throttle and the top of said reservoir, said throttle being so disposed in said passage that when closed it may mechanically and positively restrict or close said connecting passageway, the diameter of said passageway at the outlet being approximately the same as the thickness of the throttle.
- 15 3. In a carbureter adapted for connection with an engine, an air passage, a throttle in said air passage, a liquid fuel reservoir, a fuel nozzle in said passage and connected with said reservoir, and a connecting passageway confined alone to the zone of the air passage on the engine side of the throttle and the top of said reservoir, said throttle being so disposed in said passage that when closed it may mechanically and positively restrict or close said connecting passageway, the diameter of said passageway at the outlet being approximately the same as the thickness of the throttle.

In witness whereof, we hereunto subscribe our names, this 10th day of February, 1912.

EARL A. BESSOM.

RAYMOND M. ANDERSON.
